UNITED STATES PATENT OFFICE.

LEO STEINSCHNEIDER, OF BRÜNN, AUSTRIA, ASSIGNOR, BY MESNE ASSIGNMENTS, TO THE CHEMICAL FOUNDATION, INC., A CORPORATION OF DELAWARE.

PREHEATER FOR USE IN THE CHEMICAL INDUSTRY, ESPECIALLY FOR USE IN THE PETROLEUM-TAR AND THE LIKE INDUSTRY.

1,337,287.

Specification of Letters Patent.

Patented Apr. 20, 1920.

Application filed November 3, 1914. Serial No. 870,089.

To all whom it may concern:

Be it known that I, LEO STEINSCHNEIDER, a subject of the Emperor of Austria, residing at Brünn, in the Empire of Austria, 5 Franzensglacis 1, have invented a new and useful Preheater for Use in the Chemical Industry, Especially for Use in the Petroleum-Tar and the like Industry, of which the following is a specification.

10 Previous crude oil pre-heaters consist fundamentally of a horizontal vessel having arranged therein a system of horizontal tubes into which the distillate gases pass from the still-head. If such pre-heaters are to be constructed with a large capacity the dimensions become very great and therefore they require expensive foundations and surrounding walls. One great disadvantage of these 15 pre-heaters is the faulty and insufficient dephlegmation of the crude oil during the pre-heating, as the rising of the crude oil is limited, the height of rise being less than the diameter of the pre-heater vessel. It is practically proved that the best dephlegmation occurs, when the crude oil is able to rise 20 as highly as possible in the pre-heater, the water being thereby separated mechanically.

The drawing shows an example of a pre-heater according to the present invention.

25 1 is a vessel which contains the oil to be pre-heated which vessel according to the invention is arranged in an upright position. *e* is the inlet tube for the crude oil and *a* the discharge tube. 2 are the tubes of the tubular system, into and through which the distillate gases pass; 4, 5 are chambers, to which the tubes 2 are connected, preferably by expansion, in order to avoid flange-connections. 3 is the entrance tube for the distillate gases and 3' the discharge tube for the uncondensed distillate gases. In the example shown, for this purpose one of these chambers, for example the chamber 4, is provided with a partition 6, which divides the 30 chamber into two parts, from which the liquefied dephlegmantes are carried off through the outlets 7, 8. To utilize the heat contained in the condensates, the discharge of the dephlegmantes may be effected by 35 means of coils 9, 10. In the drawing 11 is the discharge tube of the coil 9, and 12 the discharge tube of the coil 10.

In order to regulate the dephlegmation in the example shown, a jacket 16 is provided,

which jacket surrounds the tubular system 55 and is capable of being shut or closed at its lower end. The closing of this jacket may be effected from the exterior by a flap valve 18 which is arranged in a narrowed tubular portion 17 of the jacket 16. If the flap is 60 moved to such position that it closes the cross sectional area of the portion 17 and thereby also closes the jacket, the entrance of new portions of oil to the tube system 2 is thereby prevented. For this reason the crude oil 65 contained within the jacket 16 will become hotter than the crude oil surrounding the outer part of the jacket. As the difference of temperature between the distillate gases and the crude oil surrounding the tube system is thereby diminished, the heat transmission of the tube system is decreased, and the production of condensates is thereby influenced.

If the pre-heater is to be constructed as a 75 combined distillate- and residue pre-heater, it is only necessary to arrange a coil 13 for the residues. In the drawing, 14 designates the inlet tube for the hot residue and 15 the outlet tube. A combined distillate and residue pre-heater of this kind offers the advantage that the total cross sectional area of the heater vessel is utilized for the passage of the oil, and that the distilling tubes and the residue coil are contained in a single 80 body.

What I claim is:

1. In a pre-heater for use in the chemical industry, an upright vessel containing the liquid to be pre-heated, a system of horizontal tubes within said vessel adapted to receive distillate gases or vapors, the heat of which vapors is adapted to heat the liquid to be pre-heated in said vessel, a jacket around said system of horizontal tubes, said jacket having a cross-sectional area less than that of said vessel, and being adapted to permit a circulation of the contents of the vessel through and around the same, and means for controlling the circulation of the 90 liquid in said vessel.

2. In a pre-heater for use in the chemical industry, an upright vessel containing the liquid to be pre-heated, the height of said vessel being greater than the dimension 95 thereof in the horizontal direction, a system of horizontal tubes, manifolds at the ends of said tubes, horizontal partitions in one of

said manifolds; a pipe leading to each of the sub-divisions of said manifold adapted to carry off condensates, said tube system being adapted to heat the liquid to be pre-heated in 5 said vessel, a residue coil located in the lower part of said vessel below the system of horizontal tubes, a jacket around said system of horizontal tubes, said jacket having a cross-sectional area less than that of said vessel, 10 and being adapted to permit a circulation of

the contents of the vessel through and around the same, and means for controlling the circulation of the liquid in said vessel.

In witness whereof I have hereunto signed my name in the presence of two subscribing 15 witnesses.

LEO STEINSCHNEIDER.
